UNITED STATES PATENT OFFICE.

RICHARD H. GOLDEN, OF SOUTH NORWALK, CONNECTICUT.

ANKLE-SUPPORTER.

SPECIFICATION forming part of Letters Patent No. 398,892, dated March 5, 1889.

Application filed July 26, 1888. Serial No. 281,064. (No model.)

To all whom it may concern:

Be it known that I, RICHARD H. GOLDEN, a citizen of the United States, residing at South Norwalk, in the county of Fairfield and State 5 of Connecticut, have invented certain new and useful Improvements in Ankle-Supporters; and I do hereby declare the following to be a full, clear, and exact description of the invention, such as will enable others skilled 10 in the art to which it appertains to make and use the same.

This invention is an improvement upon the constructions shown in Letters Patent to John G. Pugsley, No. 212,261, dated February 11, 15 1879; No. 216,106, dated June 3, 1879, and No. 346,606, dated August 3, 1886, of all of which I am joint owner with the said Pugsley.

The object of my invention is to so improve the details of construction as to add greatly 20 to the firmness and durability of the supporters, thereby greatly improving their operation in use.

With these ends in view I have devised the 25 novel improvements in the details of construction which I will now describe, referring by numbers to the accompanying drawings, forming a portion of this specification, in which—

Figure 1 is an elevation of the blank from 30 which the supporter is made; Fig. 2, a perspective of the blank bent to form, but not secured; Fig. 3, a longitudinal section of the finished supporter; Fig. 4, a perspective of a finished supporter, and Fig. 5 a plan view of 35 one of the finishing-strips.

The blank is made of stiff material, preferably leather or stiffened felt, and is usually beveled, as shown in Patent No. 346,606, referred to. The present blank is of nearly the 40 same shape as in the said former patent, with the exception that it is made longer, the proportions of the blank being such that when the supporter is formed the bottom is made to consist, primarily, of two full plies of the 45 material thereof. In Fig. 1 the dotted line denotes the lower end of the blank, as shown in the said Patent No. 346,606, and as the supporters have heretofore been manufactured the portion below the dotted line being the 50 portion used to form the solid double bottom of the completed supporter.

1 denotes the sides of the supporter, and 2 and 3 the upper and lower plies, respectively, of the double bottom. In practice these two plies are lapped over each other and are 55 riveted, eyeleted, or cemented together. The bottoms are then finished by the inner ply, 4, and the outer ply, 5, which need not be very heavy, but which give an inner and outer finish to the completed article and add 60 more or less to its strength. The eyelets, when used, may or may not pass through either the inner or outer plies, or both, the main strength of the completed bottom being secured by plies 2 and 3 of the material of 65 the supporter, which are of course firmly secured together.

Another difficulty which has heretofore existed in connection with this class of supporters has been that they have not been provided with any means of adjustment to different sizes of ankles. If the ankles were large, the supporters were quickly sprung out of place and lost their efficiency. If the ankles were abnormally small, the full effect of 75 the supporters was not gained; and, furthermore, in walking and in warm weather it has been found very desirable that means should be provided whereby the supporters might be loosened and drawn up. I have therefore 80 provided lacing-holes 6 at the front, so that they may be laced across the front in the same manner as the upper portion of an ordinary shoe.

Having thus described my invention, I 85 claim—

An ankle-supporter the body of which consists of a single piece of material and the bottom of which has two full overlapping plies integral with the said body, and independent plies 4 and 5, secured to the inner and outer of the said overlapping plies, the said body being provided at its front side with lacing-holes, substantially as set forth. 90

In testimony whereof I affix my signature in 95 presence of two witnesses.

RICHARD H. GOLDEN.
